Primary Examiner — Susan Bennett Hattan*Assistant Examiner* — Omeed Agilee(74) *Attorney, Agent, or Firm* — Workman Nydegger(57) **CLAIM**

The ornamental design for a maternal belly band, as shown and described.

DESCRIPTION

FIG. 1 is a perspective view of a maternal belly band showing our new ornamental design.

FIG. 2 is a front elevation view thereof.

FIG. 3 is a back elevation view thereof.

FIG. 4 is a top, plan view thereof.

FIG. 5 is a bottom plan view thereof.

FIG. 6 is a left elevational view thereof; and,

FIG. 7 is a right elevational view thereof.

Objects shown in broken lines are shown for environmental purposes only and form no part of the claimed design.

1 Claim, 4 Drawing Sheets(56)
